(57) **CLAIM**

We claim, the ornamental design for an electrical contact device, as shown and described.

DESCRIPTION

FIG. 1 is a front perspective view of a first embodiment of an electrical contact device showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a rear perspective view thereof;

FIG. 9 is a front perspective view of a second embodiment thereof;

FIG. 10 is a front view thereof;

FIG. 11 is a rear view thereof;

FIG. 12 is a front perspective view of a third embodiment thereof;

FIG. 13 is a front view thereof;

FIG. 14 is a rear view thereof;

FIG. 15 is a front perspective view of a fourth embodiment thereof;

FIG. 16 is a front view thereof;

FIG. 17 is a rear view thereof;

FIG. 18 is a front perspective view of a fifth embodiment thereof;

FIG. 19 is a front view thereof; and,

FIG. 20 is a rear view thereof.

The shade lines in the figures show contour and not surface ornamentation.
